(57) **CLAIM**

The ornamental design for a post cap light, as shown and described.

DESCRIPTION

FIG. 1 is a perspective view of the post cap light.

FIG. 2 is a front elevational view of the post cap light shown in FIG. 1.

FIG. 3 is a right side elevational view of the post cap light shown in FIG. 1.

FIG. 4 is a rear elevational view of the post cap light shown in FIG. 1.

FIG. 5 is a left side elevational view of the post cap light shown in FIG. 1.

FIG. 6 is a top plan view of the post cap light shown in FIG. 1; and,

FIG. 7 is a bottom plan view of the post cap light shown in FIG. 1.

Broken lines illustrate features or environmental components that are not part of the design sought to be patented.
